TROUSER AND SKIRT HANGER

Raymond P. Hartz, East Windsor, N. Y.

Application September 13, 1944, Serial No. 553,887

2 Claims. (CL 223—95)

This invention relates to new and useful improvements in garment hangers, and more particularly to a hanger for supporting pants and skirts.

The principal object of the present invention is to provide a hanger of the expandable type especially adapted for hanging ladies' skirts by their waist portions or trousers by their cuff portions.

Another important object of the invention is to provide a simple and easily operable hanger which can be readily expanded to accommodate garments of various sizes.

These and other important objects and advantages of the invention shall become apparent to the reader of the following description.

In the drawing:

Figure 1 represents a side elevational view of the hanger.

Figure 2 is a section taken on line 2—2 of Figure 1.

Figure 3 is a section taken on line 3—3 of Figure 1 (enlarged).

Figure 4 is an enlarged fragmentary detailed sectional view taken on line 4—4 of Figure 1.

Referring to the drawing, wherein like numerals designate like parts, it can be seen that numeral 5 denotes an elongated bar provided with a hook 6 at its upper end. This bar has an elongated longitudinal slot 7 therein through which a bolt 8 is disposed, this bolt being intended to project through openings 9 and 10 in links 11, 12, respectively. The bolt 8 is equipped with a wing nut or the like 13.

At the lower end position of the bar 5 is an opening through which a bolt 14 is disposed, and this is equipped with a wing nut or the like 15. The bolt 14 is disposed through openings 16 and 17 in link bars 18, 19, respectively.

The outer ends of the link bars 12, 19 are crossed and pivoted together, as at 20, just inwardly of their ends, while the bars 11, 18 are likewise pivoted together, as at 21.

A pair of garment-engaging units 22, 23 are provided at the outer ends of the two pairs of link bars just described.

Each of these garment-engaging units 22, 23 consists of a U member 24 having outwardly and downwardly disposed portions defining fingers 25, 26 which are serrated at their outer edges, as at 27, to firmly grip a garment.

The unit 22 has the adjacent end of the link bar 18 pivoted to the U-shaped member 24, as at 28, while the lower portion of the U-shaped member 24 is slotted, as at 29, to accommodate a bolt 29 which passes through the adjacent end of the link bar 11.

The link bars 12, 19 are likewise connected to the garment-engaging unit 23.

It can be seen that due to the shouldered construction of the bolts 8, 14, and the wing nuts 13, 15 bearing against the shoulders and not binding

the corresponding bars 11, 12, 18, 19, these pivot points are always free. The pants are applied to the hanger by engaging the ends of one cuff with the fingers 25 at one side of the hanger and the other cuff with the fingers at the other side of the hanger and by pushing the bolt 8 or the bars 11, 12 toward the bars 18, 19 the hanger will be expanded and the weight of the garment will serve when the hanger is disposed upright in maintaining the hanger expanded and the garment properly suspended.

A lady's skirt can be supported by simply inserting the hanger within the waistband of the skirt and expanding the same to firmly grip the skirt.

Thus, it can be seen that by the use of this hanger, the garments are in no way creased such as occurs when pants are hung over coat hangers and skirts are likewise hung.

While the foregoing description sets forth the invention in specific terms, it is to be understood that numerous changes in the shape, size and materials may be resorted to without departing from the spirit and scope of the invention as claimed hereinafter.

Having described the invention, what is claimed as new is:

1. A garment hanger comprising a pair of garment-gripping units, a bar having suspending means at one end thereof from a pair of crossed link bars pivotally secured together and being connected to one of the units, a second pair of link bars pivotally connected together and secured to the other unit, one link bar of each pair being disposed over one end of the first-mentioned bar, securing means between the last-mentioned link bars and the first-mentioned bar, and an adjustable connection between the remaining link bars and the first-mentioned bar, each of said units consisting of a U-shaped member having outwardly and downwardly disposed pants cuff engaging fingers.

2. A garment hanger comprising a pair of garment-gripping units, a bar having suspending means at one end thereof from a pair of crossed link bars pivotally secured together and being connected to one of the units, a second pair of link bars pivotally connected together and secured to the other unit, one link bar of each pair being disposed over one end of the first-mentioned bar, securing means between the last-mentioned link bars and the first-mentioned bar, and an adjustable connection between the remaining link bars and the first-mentioned bar, each of said units consisting of a U-shaped member having outwardly and downwardly disposed pants cuff engaging fingers.

45 3. A garment hanger comprising a pair of garment-gripping units, a bar having suspending means at one end thereof from a pair of crossed link bars pivotally secured together and being connected to one of the units, a second pair of link bars pivotally connected together and secured to the other unit, one link bar of each pair being disposed over one end of the first-mentioned bar, securing means between the last-mentioned link bars and the first-mentioned bar, and an adjustable connection between the remaining link bars and the first-mentioned bar, each of said units consisting of a U-shaped member having outwardly and downwardly disposed pants cuff engaging fingers.

50 4. A garment hanger comprising a pair of garment-gripping units, a bar having suspending means at one end thereof from a pair of crossed link bars pivotally secured together and being connected to one of the units, a second pair of link bars pivotally connected together and secured to the other unit, one link bar of each pair being disposed over one end of the first-mentioned bar, securing means between the last-mentioned link bars and the first-mentioned bar, and an adjustable connection between the remaining link bars and the first-mentioned bar, each of said units consisting of a U-shaped member having outwardly and downwardly disposed pants cuff engaging fingers, the link bars at their outer ends being secured to the garment-engaging unit within the said U-shaped members.
